UNITED STATES PATENT OFFICE.

FRANK H. OTIS, OF SKANEATELES, NEW YORK.

METHOD OF MAKING ELBOWS FROM SHEET METAL.

Application filed March 20, 1924. Serial No. 700,720.

To all whom it may concern:

Be it known that I, FRANK H. OTIS, a citizen of the United States, and resident of Skaneateles, in the county of Onondaga and 5 State of New York, have invented certain new and useful Improvements in Methods of Making Elbows from Sheet Metal, of which the following is a specification.

The present invention relates to a method 10 of making elbows from sheet metal and more particularly to the type in which the elbow has but a single seam and is free from ribs or corrugations for obtaining the bend. An object of this invention is to provide an improved method which will make it possible 15 to obtain the elbow from a minimum amount of stock without extreme stretching of the metal.

To this and other ends, the invention consists of certain parts and combinations of parts, all of which will be hereinafter described: the novel features being pointed out in the appended claims.

In the drawings:

25 Fig. 1 is a plan view of a blank after it has been subjected to the first or stamping operation;

Fig. 2 is a section on the line 2—2, Fig. 1;

30 Fig. 3 is a plan view of the blank after it has been subjected to the second or trimming operation;

Fig. 4 is a side view of the blank after it has been subjected to the third or stamping operation;

35 Fig. 5 is an end view after it has been subjected to the third operation;

Fig. 6 is a plan view after it has been subjected to the fourth stamping operation;

40 Fig. 7 is a side view of the blank after it has been subjected to the fourth operation;

Fig. 8 is an end view of the blank as produced by the fourth operation;

45 Fig. 9 is a side view of the blank after it has been subjected to the fifth or stamping operation;

Fig. 10 is a section on the line 10—10, Fig. 9;

Fig. 11 is a side view of the completed elbow;

50 Fig. 12 is a section on the line 12—12, Fig. 11; and

Fig. 13 is an enlarged section through the seam.

In carrying out this invention a flat piece 55 of sheet material preferably of circular form is subjected to a shaping operation prefer-

ably by pressing in which a cup shaped portion 1 is produced surrounded by an annular flange 2. The next operation consists in cutting the flange 2 of the blank produced 60 in Fig. 1 to provide arms 3 which widen at their inner ends and merge into the perimeter of the cup shaped portion 1. The next operation consists in shaping the cup shaped portion so that it becomes elongated or narrowed as at 4 on an axis transversely of the blank shown in Fig. 3, and at the same time the arms 3 are bent at their inner ends so that they lie in parallel relation as shown at 5 and in planes at right angles to the plane 65 of the elongated cup shaped portion 4.

The fourth operation illustrated in Figs 6, 7 and 8 consists in bending the parallel arms 5 of Figs. 4 and 5 to provide concave arms 6. The fifth operation consists in bending the arms inwardly over the elongated cup shaped portion and, at the same time, curving them so that a tubular elbow 7 is provided substantially oval in cross section as shown in Fig. 10, the adjacent free edges of 75 the arms being slightly separated. The sixth operation consists in seaming the meeting edges of the blank together as shown at 8, Figs. 12 and 13, and, at the same time, reshaping the tubular member so that it has a 80 substantially circular cross section showing the complete elbow as in Figs. 11 and 12.

From the foregoing it will be seen that there has been provided an improved method of forming elbows from sheet metal so that 85 the elbow has a single seam and is free from transverse creases or bends. It will be noted that the trimming or cutting operation occurs after the first pressing operation. This is desirable as this pressing operation 90 stretches the metal and will destroy the general outline of the original blank, making it possible to provide a uniform blank in the first instance. It will also be noted that applicant obtains the elongated cup portion by 95 two operations, one a cylindrical cup portion and then the final elongated cup portion.

What I claim as my invention and desire to secure by Letters Patent is:

1. The method of forming sheet metal elbows which consists in shaping a flat sheet to provide a circular cupped portion and a flange beyond said cupped portion entirely surrounding said cupped portion, removing the flange except at two diametrically opposite portions to provide two projections, the inner ends of which widen and merge in 100

to the perimeter of the cupped portion, shaping the cupped portion to narrow the same in a direction transversely of the length of the projections, and, at the same time, bending the projections and portions of the cupped portion to provide flattened portions extending in one direction at angles to the general plane of the elongated cupped portion, concaving the outer faces of the flattened portions, and bending the concave portions toward each other so that their meeting edges may be interlocked.

2. A method of forming sheet metal elbows which consists in shaping a flat piece to provide a circular cup portion and a flange beyond said cup portion, removing the flange except at two diametrically opposite portions to provide two projections, and thereafter narrowing the cup portion in a direction transversely of the elbow and bending the projections to bring their edges into interlocking relation.

3. A method of forming sheet metal elbows which consists in shaping a flat sheet to provide a circular cupped portion, and a flange beyond said cupped portion, removing the flange except at two diametrically opposite portions to provide two projections, shaping the cupped portion to narrow the

same, in a direction transversely of the length of the elbow and, at the same time, bending the projections to cause them to extend in one direction at right angles to the plane of the elongated cupped portion, and thereafter curving and bending the projections to bring them into interlocking relation.

4. A method of forming sheet metal elbows which consists in shaping a flat sheet to provide a circular cupped portion and a flange beyond said cupped portion, removing the flange except at two diametrically opposite portions to provide two projections, narrowing the cupped portion in a direction transversely of the length of the elbow and, at the same time, bending without curving the projections to cause them to extend parallel with each other and at right angles to the original plane of the sheet, concaving the outer faces of the projections to cause them to extend over the cupped portion while, at the same time, providing the inner curve of the elbow and thereafter bending the projections toward each other to provide the curved outer sides of the elbow.

FRANK H. OTIS.
